UNITED STATES PATENT OFFICE

RUDOLF KARG AND JOSEF WEISS, OF LUCERNE, SWITZERLAND

PROCESS OF PRODUCING INSULATING SHEETS

Application filed September 27, 1927, Serial No. 222,303, and in Switzerland October 4, 1928.

This invention consists in a process of producing insulating sheets by the utilization of a fibrous, vegetable material, for example wood wool, shavings, rushes, straw and so forth, and magnesite.

The process is characterized in that the fibrous material with addition of magnesite is saturated with an aqueous solution of a product which has the property of binding with the magnesite, allowed to drain, laid in perforated moulds and dried.

Kieserite, bitter salt, Glauber salt and so forth may be employed as the substance for binding of the magnesite.

15 The magnesite can be added to the solution of the products with which it binds or it can be added in dust form to the vegetable material treated with the solution.

The moulds may for example consist of a 20 frame with a perforated bottom of wire web, a stretching net, a sieve and so forth, which is closed with a cover which may also be perforated.

The drying of the sheets can take place in 25 in the air or in special drying ovens.

The perforation of the mould has the purpose of facilitating the escape of the vapours which develop during the drying out.

To produce such plates, kieserite is for example dissolved in water, then some magnesite is added to this solution and wood wool is then dipped in, removed, allowed to drain, placed in moulds and thereupon dried. Furthermore the same solution can 35 be prepared, the wood wool dipped in, drawn out and dusted with magnesite, laid in the moulds and dried therein.

The sheets so produced can be covered on 40 one or both sides with a layer of cement, gypsum, artificial wood and the like. To this end, this material is applied in the manner of plaster or the insulating sheet is placed in a fresh mould which is partly filled with this covering material and the sheet is taken 45 out after the covering has hardened.

In order to strengthen the insulating plate, the same may be reinforced, for example with wood laths. To this end these laths 50 are embedded in the fibrous material and

the material is allowed to harden in the moulds.

The plates can also be provided on the smaller sides with grooves and tongues by providing corresponding cavities in the 55 moulds.

These tongues and grooves may also be provided on the outer reinforcing strips by correspondingly profiling these strips.

Furthermore the grooved and tongued 60 edges can be formed of casein glue or other suitable glue or cement, by filling the moulds having corresponding cavities with the glue or cement at the edges and stamping the fibrous material inside the same.

Constructional examples of such covered plates are illustrated in the accompanying drawings, wherein—

Figures 1, 2 and 3 respectively show such a plate without reinforcements, in edge view, 70 face view and cross section.

Figures 4, 5 and 6 show similar views of a reinforced plate in which the covering is also provided with a profile and in which both of the outer reinforcing strips are provided with a slot and key.

Figure 7 is a cross section showing a part of a plate in which the edge consists of artificial wood for the reception of the slot or key.

Referring now more particularly to Figures 1, 2 and 3, 1 designates a sheet, plate or board, such as wall board, provided with a hardened plastic insulating sheet or facing 2 embodying my invention and which may be provided on its outer surface with a beading or other ornamentation 5. As shown, the boards may be provided with interengaging grooved and tongued edges 3 and 4. In the form of the invention shown in Figures 4, 5 and 6, the boards 1 are provided with reinforcing members such as laths 6, embedded therein, the laths at the edges of the boards being provided with tongues 7 and grooves 8. Figure 7 shows a construction in which the marginal edge 9 of the board, in which the groove 10 of a coacting tongue, is formed, is made up of casein glue or other suitable glue or cement, as hereinbefore described.

An objection to insulating sheets or facings 100

of the kind commonly in use is that many of these embody a binding material containing chlorine or constituted so that the material does not adhere firmly and permanently to the board. It has heretofore been found particularly difficult to find a binding medium which is suitable for use with magnesite and at the same time will provide a firm binder of the elements of the plastic composition forming the sheet or facing and adapt the latter to adhere firmly to the wall board. By the use of kieserite these objections are overcome and a binder provided, which is highly efficient for use in compositions containing magnesite and causes such compositions to adhere with great tenacity to the wall board. Kieserite is greatly superior to Epsom salt, as while it is soluble in hot water, it is not, like Epsom salt, soluble in cold water, and hence acts to a desirable degree as a waterproofing agent. Kieserite is also very cheap and the drying process is much more rapid with it than where Epsom salt, sulphate radical or other binders are used.

Having now particularly described and ascertained the nature of our said invention and in what manner the same is to be performed, we declare that what we claim is—

1. A process for producing insulating sheets, which consists in placing a vegetable fibre in a solution of kieserite and magnesite and causing said fibre to take up a proportion of the solution, removing the fibre from the solution and draining therefrom any surplus solution, and molding the sheet from the so treated fibre in a mold perforated to permit evaporation of the moisture in the fibre.

2. A molded insulating sheet formed from a vegetable fibre which has been subjected to the action of a solution of kieserite and magnesite and molded therefrom.

In testimony whereof they affix their signatures.

RUDOLF KARG.
JOSEF WEISS.
